UNITED STATES PATENT OFFICE

WALTER F. BAKER, OF NEWPORT NEWS, VIRGINIA

MANIFOLD BOOKBINDER

Application filed January 24, 1930. Serial No. 423,159.

This invention relates to manifold books and more particularly to the binding therefor.

Manifold books have usually been bound with a hinge for the top cover on top of the book while the hinge for the bottom cover, if there was any, was at the bottom of the book. With the hinge at the bottom of the back bone of the book the top cover when folded beneath the book would project beyond the front end thereof a distance equal to the thickness of the book. It was to overcome this objectionable feature and to effect a saving in time and material that this invention was designed.

A primary object of the invention is to so bind a book of this character that much time and material will be saved in the manufacture and a degree of convenience provided not heretofore had.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a perspective view of a portion of a book constructed in accordance with this invention with the top cover member shown partially open;

Fig. 2 is a top plan or end view of the closed book with parts broken out for convenience in illustration; and

Fig. 3 is an end view with the top cover folded back under the book, and the intermediate portions of the strips shown detached from the back bone of the book to more clearly illustrate their structure.

The portion termed "backbone" of a book is the rear portion where the leaves are connected and which is shown at 4 in the drawings.

The illustration which shows a preferred embodiment of the invention comprises a manifold book 1 including leaves 5 and cover members 2 and 3 connected in a manner presently to be described, and having a backbone 4. The leaves 5 constituting the body portion of the book are bound together at

their rear edges forming a back bone and to the rear edge of the bottom cover member 3 by staples 6 in the manner usual with books of this type.

Two strips 7 and 8 of tough, strong, flexible fabric are provided and one of them (7) is glued along one edge to the outer face of the top or uppermost leaf 5a adjacent the back bone 4 and along its other edge is glued to the inner face of the cover member 2 adjacent its rear end. The other strip 8 is glued along one edge to the outer face of the bottom member 3 adjacent the back bone and along its other edge is glued to the outer face of cover member 2 adjacent its rear edge. The intermediate portion of strip 7 between its attached edges is of a length to span the width of the back bone or the space between leaf 5a and cover 2 when the latter is folded back under cover 3 (see Fig. 3). One-half of the intermediate portion of strip 7, that is, the portion between its connected edges, is secured, preferably by gluing, to the back bone 4 from a point adjacent the connection of said strip with the leaf 5a to a point midway of the width of the back bone, (see Fig. 1). The intermediate portion of strip 8, or the portion between its attached edges, is of a length corresponding to the width of the back bone 4 and is glued to said back bone from the point of attachment of said strip to cover 3 to the point on the back bone where the intermediate glued portion of strip 7 stops, (see Fig. 1). At their point of meeting the strips 7 and 8 are placed in contact with each other and glued together for a distance equal to the space between their points of meeting and the rear edge of top member 2 of the book. At this point the strips 7 and 8 are separated and the top member 2 has its rear edge inserted between them, and the strips are glued, the one 8 to the outer face and the other 7 to the inner face, of said top member 2 as is shown clearly in Fig. 1. It will thus be seen that a hinge connection 9a is formed intermediate the width of the back bone 4 by the inner edges of the glued together portions of the two strips 7 and 8 so that when the top member 2 of the book is in closed position it will

lie flat down over the outer leaf 5a and the portion of strip 7 which is glued to the back bone of the book. When cover 2 is in open position as shown in Fig. 3 the hinge portion 9 will fold down over the portion of strip 8 which is glued to the back bone and permits the top cover member 2 to fold flat under the book overlying cover 3 so that the front edge of member 2 when so folded will be flush with the front edge of the bottom member 3 and thus permit the book to be laid flat on the desk without any projecting of the cover members in substantially the same manner as if they were no top cover member.

It will thus be seen that the hinge of this book which connects the swingable cover member 2 is made midway the width of the backbone of the book half way between the top and bottom of the back bone but obviously it need not be positioned exactly half way but may be at any intermediate point. The construction of this connection of the covers results in the saving of considerable material, less than one-third that required in binding the old ordinary "flap back style" of manifold.

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed.

I claim:

In combination with a book body including leaves secured together at their rear edges to form a back bone; of covers for said body, flexible hinge strips, one strip secured along one edge to one side of said body adjacent said back bone and the other strip secured along one edge to the outer face of one cover member, said strips being glued to the back bone and meeting intermediate the width of the back bone and secured together a distance equal to the distance from the meeting point of the strips to the body face to which one strip is attached, said strips having their other edges straddling the rear edge of the other cover member and secured thereto.

WALTER F. BAKER.
